UNITED STATES PATENT OFFICE.

AUGUST L. BECHTEL, OF CLEVELAND, OHIO, ASSIGNOR TO THE CLEVELAND PUNCH AND SHEAR WORKS, OF CLEVELAND, OHIO, A CORPORATION OF OHIO.

TOOL-OPERATING MACHINE.

1,203,171.

Specification of Letters Patent. Patented Oct. 31, 1916.

Application filed April 8, 1916. Serial No. 89,884.

To all whom it may concern:

Be it known that I, AUGUST L. BECHTEL, a citizen of the United States, residing at Cleveland, in the county of Cuyahoga and 5 State of Ohio, have invented a certain new and useful Improvement in Tool-Operating Machines, of which the following is a full, clear, and exact description, reference being had to the accompanying drawings.

10 This invention relates to tool operating machines of the type wherein a tool (such as a punch) is carried by a reciprocable head and is moved thereby into operative relation to the work, and has for its general 15 object to provide a machine of this character wherein the tool will be automatically disconnected from the head after the operating movement.

In the embodiment disclosed herein, the 20 invention is applied to a punch press and is employed for the purpose of automatically disconnecting the punch post or holder from the head as soon as the latter has moved a predetermined distance on the 25 return stroke, thus enabling the automatic disconnection to be accomplished at the conclusion of the stripping movement, the punch remaining so disconnected until such time as desirable to punch the next hole in 30 the work. This capability of action is particularly useful for the purpose of centering the punch upon the work.

In the embodiment of my invention disclosed herein, there is employed a fixed member or frame on which the work is supported, a head movable toward and from this fixed member or frame, said head having a guideway therein for a punch holder or post, an abutment, shown specifically as a gag 35 movable across said guideway to render the punch operative or inoperative, as occasion may require, and automatically-operating means for engaging the punch post or holder and adapted to move it a predetermined distance away from the work, for stripping purposes, and to release it after such stripping movement.

In the drawings, Figure 1 represents a 40 front elevation of the fixed member and part of the movable member or head of a punch press having my invention applied thereto; Fig. 2 an enlarged detail, partly in section and partly in elevation, of the parts shown in the preceding figure, the punch post or 45 holder being shown in its elevated position;

Fig. 3 a vertical sectional view corresponding substantially to the line 3-3 of Fig. 2, the punch, with its holder or post and the gag, being shown in elevation; and Fig. 4 a detail similar to Fig. 2 showing the position of the parts during the punching stroke. 60

Describing by reference characters the various parts illustrated herein, 1 denotes the movable head, 2 the fixed member or frame, 3 the work or sheet to be punched and 4 the punch proper having the usual seat 5. The parts described are of usual or standard construction, the punch being connected in the usual manner to the post 6. 65

The post 6 is reciprocably mounted in a guideway provided within the head. This guideway is preferably provided in a wedge-shaped or dove-tailed block 7 fitting in a correspondingly-shaped recess extending transversely of the head. The block 7 is provided with a bore which substantially sizes and guides the post 6, the upper end of the post projecting into an enlarged opening 8 extending transversely of the head and provided above the post with a guideway wherein is slidably mounted the gag 9 having the usual operating handle 10. The post 6 is provided with a key slot 11 extending substantially parallel with the axis thereof and which receives the inner end 12 of a screw 13, thereby to prevent the post from turning and in effect providing a sliding keyway between the post and the block 7. The block 7 constitutes a holder whereby the punch and its post may be conveniently applied to and removed from the head. 80

14 denotes a plunger which is movable transversely with respect to the head and punch holder and which is slidable within said head and the holder, the head and the holder being provided with registering bores. The bore in the head is enlarged at its outer portion, as indicated at 15, whereby it may receive therewithin a sleeve 16 having its outer end projected through the head and provided with a cap or closure 17. The sleeve is conveniently secured in place by means of an externally threaded sleeve 18 having an operating head 19 adapted to receive a wrench, the inner or threaded end of the sleeve being adapted to engage a shoulder 16^a on the sleeve. A spring 20 bears at one end against the bottom of the enlarged bore 15 and at its opposite end against the sleeve 16, and tends to hold the 100

95

105

110

same in the position shown in Fig. 2, while the weaker spring 21, interposed between the cap 17 and the plunger 14, presses the latter inwardly or toward the post 6. The 5 post is provided with a vertical slot 22 which is adapted to receive therewithin the adjacent end of the plunger when the plunger and the slot are in register. A pin 23 carried by the plunger 14 enters a slot 24 carried by the sleeve 16 providing a lost-motion connection between these parts. The outer end or cap of the sleeve is provided with a beveled or cam face 25 which cooperates with a beveled or cam face 26 on a 10 block 27 carried by the head. This block 27 is adjustable in the direction of the length of the punch post, being secured by means of bolts 28 extending through slots 29 in an angle plate 30 which is secure to a fixed 15 part of the press, as by means of screws 31. In the operation of ordinary punch presses, the plate to be punched is provided with small center-punch marks indicating the centers of the holes to be punched by 20 the press. It takes considerable time to position the plates so that these marks shall be in axial alinement with the punch. The press shown and described herein is designed to facilitate this position or centering 25 of the plate, by allowing the punch to rest upon the plate during the entire or any desired portion of each reciprocation of the head.

The operation is briefly as follows: The 30 plate 3 is applied to the fixed member or frame 2 so as to bring the desired center-punch mark in axial alinement with the punch seat. The gag 9 being in position, the head is reciprocated and the punch 4 is forced through the plate by the gag. During this operation, the parts will be in substantially the positions shown in Fig. 4; that is to say, the head of the punch post is engaged by the gag and, when the post is in 35 this position, the upper end of the slot 22 is brought into register with the adjacent end of the plunger 14. This, however, because of the engagement of the pin 23 with the end of the slot 24, could not enter the slot 40 22 but for the fact that the cam 26 on the block 27 has meanwhile engaged and pushed inwardly the sleeve 16, which will move the slot 24 toward the post and will permit the spring 21 to thrust the plunger 14 into the slot 22. It will be seen that the movement of the punch on the down stroke of the head is accomplished through the engagement of the upper end of the punch post with the gag 9. On the return stroke of the head, 45 the punch is lifted through the engagement of the plunger 14 with the abutment formed at the top of the slot 22 but is lifted only until such time as the sleeve cap or head 17 clears the cam block 27, at which time the 50 spring 20—being stronger than the spring

21—thrusts the sleeve outwardly and with it the plunger 14, through the engagement of the pin 23 with the inner end of the slot 24, whereupon the parts assume the positions shown in Fig. 2—with the punch resting on the plate 3. 70

In practice, the cam plate 27 will generally be so set as to permit the point of the punch 4 to clear the plate 3 about one-sixteenth inch before the post is disconnected from the head. On the completion of the punching stroke, the operator withdraws the gag 9. The driving connection between the head and the punch post is then broken and the punch will rest upon the plate and there will be no further punching stroke until the gag is reinserted. Until such time the head merely reciprocates about the post. On the down stroke of the head, the plunger 14 will necessarily enter the slot 22 and, on the upstroke of the head, the parts will preferably be arranged so that the plunger 14 will engage the top of the slot 22 and lift the punch—say about one-sixteenth inch above the work—before the cam head of the sleeve rides off the block 27; when this happens, the plunger will be moved out of the slot 22 in the manner before described, and the punch will drop upon the work. The gag will remain out of operative relation to the top or head of the punch post until such times as the plate has been centered beneath the punch. It will then be reinserted and the plate will be punched in the manner described hereinbefore. If desired, provision may be made for withdrawing the gag automatically at the end of the punching stroke and for reinserting it at any desired period thereafter—say on every alternate, or every third, stroke of the head. Furthermore, 105 this gag controlling means may be made adjustable so as to vary the time of its insertion in accordance with the circumstances of any particular case. 95

It will be seen that, in the operation of the punch press herein disclosed, the head will reciprocate about the punch post or holder until such time as the gag may be inserted, the parts being preferably arranged so that the punch will be given a slight upward or stripping movement on each stroke of the head away from the work; also that, when the gag has been inserted, the punch will function in the ordinary manner to punch the work, but that means are provided whereby the punch will be moved in the reverse direction a sufficient distance only to secure the stripping from the work whereupon it will be automatically disengaged from the head. 110 115

While, for convenience of illustration, I have shown my invention applied to a single tool or punch, it will be obvious that it may be applied to all of the tools or punches of a multi tool or punch press. As many 120 125 130

- tool holders or posts as may be desirable may have their operating cam faces arranged in substantially the same horizontal plane and be operated by a common cam 5 plate or by a suitable number of individual cam plates whereby the tools or punches will be simultaneously stripped from the work when the head has moved a predetermined distance on the return stroke.
- 10 Having thus described my invention, what I claim is:—
1. In a machine of the character described, the combination of a work supporting member, a movable member or head reciprocable 15 toward and from the work supporting member and having a tool-engaging abutment, a tool reciprocably mounted in the movable member, means other than the abutment for automatically connecting the tool to the 20 head during the movement of the head toward the work, and means for automatically breaking such connection when the head has moved a predetermined distance from the work.
  - 25 2. In a machine of the character described, the combination of a work supporting member, a movable member or head reciprocable toward and from the work supporting member, a tool reciprocably mounted in the movable member, an abutment carried by the movable member and adapted to be brought into and out of operative relation to the tool, means other than the abutment for automatically connecting the tool to the head 30 35 for the purpose of moving the tool away from the work, and means for automatically breaking such connection when the head has moved the tool a predetermined distance from the work.
  - 40 3. In a punch press, the combination of a work supporting member, a head movable toward and from the work supporting member, said head having a guideway, a punch post or support reciprocably mounted in said guideway, a gag movable across the guideway and into and out of operative relation to the punch post or support, means other than the gag for connecting the punch support to the head whereby the said support will be carried by the head as the latter moves away from the work, and means for automatically breaking such connection when the head has moved a predetermined distance in such direction.
  - 45 5. In a punch press, the combination of a work supporting member, a head movable toward and from the work supporting member, said head having a guideway, a punch post or support reciprocably mounted in said guideway, a gag movable across the guideway and into and out of operative relation to the punch post or support, means other than the gag for connecting the punch support to the head whereby the said support will be carried by the head as the lat- 50 55 60 65
  6. In a machine of the character described, the combination of a work supporting member, a head reciprocable toward and from said member, a tool reciprocably mounted in said head, the head having an abutment which is adapted to engage the tool when the head is moved toward the work, a plunger reciprocably mounted in said head and adapted to engage the tool thereby to connect the same to the head during the movement of the head away from the work, and adjustable means other than said abutment for automatically breaking the connection between the plunger and the tool when the head has moved a predetermined distance from the work.
  7. The combination, with a work supporting member, of a head movable toward and from said member and having a guideway, a tool reciprocably mounted in said guideway, said tool having a notch or recess therein and said head having a guideway adapted to register with said notch or recess, a plunger mounted in the second guideway, means tending to hold said plunger away from said recess and out of engagement with the tool, and adjustable means located in the path of travel of the head and operating to project the plunger into said recess against the action of such withholding means and to resubject the plunger to the action of such withholding means when the head is moved a predetermined distance in the opposite direction.
  8. In a machine of the character described, the combination of a work supporting member, a head movable toward and from the work supporting member and having a guideway, a tool reciprocably mounted in said guideway, an abutment adapted to engage said tool as the head moves toward the work supporting member, means for automatically connecting the tool to the head

- and for automatically disconnecting the same therefrom when the tool has been moved a predetermined distance to strip the work, such automatic means comprising 5 a guideway in the head extending to the bore thereof, an abutment carried by the tool, a plunger reciprocably mounted in the last mentioned guideway, a sleeve surrounding the outer portion of the plunger and having 10 a cap, a spring interposed between said cap and the plunger and tending to thrust the plunger into engagement with the abutment on the tool, a spring bearing against the sleeve and tending to move the same away 15 from the tool, the second spring being of greater strength than the first, a lost-motion connection between the sleeve and the plunger, and adjustable means carried by a fixed part of the machine and adapted to engage the sleeve cap thereby to press the same inwardly 20 against the action of the second spring and to permit the plunger to be projected by the other spring into the recess in the tool when the head has been moved a predetermined distance toward the work and to permit such second spring to move the sleeve and 25 the plunger in the opposite direction to withdraw the plunger from the recess when the head has been moved a predetermined distance from the work on the reverse stroke of such head. 30 9. In a machine of the character described, the combination of a work supporting member, a head movable toward and from the work supporting member and having a guideway, a tool reciprocably mounted in said guideway, a gag movable across said guideway and adapted to engage said tool as the head moves toward the work supporting member, and means other than said gag for automatically connecting the 35 tool to the head and for automatically disconnecting the same when the tool has been moved a predetermined distance in a direction to strip the work. 40 10. In a machine of the character described, the combination of a work supporting member, a head movable toward and from the work supporting member and having a guideway, a tool reciprocably mounted in said guideway, a gag movable across said guideway and adapted to engage said tool as the head moves toward the work supporting member, and means other than said gag for automatically connecting the tool to the head and for automatically disconnecting the same when the tool has been moved a predetermined distance to strip the work, such automatic means comprising 45 a guideway in the head extending from the bore thereof, a recess in the tool, a plunger reciprocably mounted in the last mentioned guideway, a sleeve surrounding the outer portion of the plunger and having a cap, a spring interposed between said cap and the plunger and tending to thrust the plunger into engagement with the tool, a spring bearing against the sleeve and tending to move the same away from the tool, the second spring being of greater strength than the first, a lost motion connection between the sleeve and the plunger, and adjustable means carried by a fixed part of the machine and having an inclined surface adapted to engage the inclined surface of the sleeve and adapted to engage the sleeve cap thereby to press the same inwardly against the action of the second spring and to permit the plunger to engage the tool adjacent to the abutment when the head has been moved a predetermined distance toward the work and to permit such second spring to move the sleeve and the plunger in the opposite direction when the head has been moved a predetermined distance from the work on the reverse stroke of such head. 50 11. In a machine of the character described, the combination of a work supporting member, a head movable toward and from the work supporting member and having a guideway, a tool reciprocably mounted in said guideway, a gag movable across said guideway and adapted to engage said tool as the head moves toward the work supporting member, and means other than said gag for automatically connecting the tool to the head and for automatically disconnecting the same when the tool has been moved a predetermined distance to strip the work, such automatic means comprising 55 a guideway in the head extending from the bore thereof, a recess in the tool, a plunger reciprocably mounted in the last mentioned guideway, a sleeve surrounding the outer portion of the plunger and having a cap provided with an inclined or cam surface, a spring interposed between said cap and the plunger and tending to thrust 60 the plunger into the recess in the tool, a spring bearing against the sleeve and tending to move the same away from the tool, the second spring being of greater strength than the first, a lost-motion connection between the sleeve and the plunger, and adjustable means carried by a fixed part of the machine and adapted to engage the sleeve cap thereby to press the same inwardly against the action of the second spring and to permit the plunger to be projected by the other spring into the recess in the tool when the head has been moved a predetermined distance toward the work and to permit such second spring to move the sleeve and the plunger in the opposite direction to withdraw the plunger from the recess when the head has been moved a predetermined distance from the work on the reverse stroke of such head. 65 12. In a machine of the character described, the combination of a work-supporting member, a head movable toward and from the work-supporting member and having a guideway, a tool reciprocably mounted in said guideway, a gag movable across said guideway and adapted to engage said tool as the head moves toward the work supporting member, and means other than said gag for automatically connecting the tool to the head and for automatically disconnecting the same when the tool has been moved a predetermined distance to strip the work, such automatic means comprising a guideway in the head extending from the bore thereof, a recess in the tool, a plunger reciprocably mounted in the last mentioned guideway, a sleeve surrounding the outer portion of the plunger and having a cap provided with an inclined or cam surface, a spring interposed between said cap and the plunger and tending to thrust the plunger into the recess in the tool, a spring bearing against the sleeve and tending to move the same away from the tool, the second spring being of greater strength than the first, a lost-motion connection between the sleeve and the plunger, and adjustable means carried by a fixed part of the machine and adapted to engage the sleeve cap thereby to press the same inwardly against the action of the second spring and to permit the plunger to be projected by the other spring into the recess in the tool when the head has been moved a predetermined distance toward the work and to permit such second spring to move the sleeve and the plunger in the opposite direction to withdraw the plunger from the recess when the head has been moved a predetermined distance from the work on the reverse stroke of such head.

said head having an upper and a lower slideway, a gag slidable in the upper slideway, a dovetailed block slidable in the lower guideway and having a vertical bore, and a 5 tool post or support slidably mounted in said bore.

13. In a machine of the character described, the combination of a work supporting member, a head movable toward and 10 from said member, said head having a slideway therein, a block mounted in said slideway and having a bore, a tool-supporting post reciprocably mounted in said bore, said head having a plunger adapted to engage 15 the tool-supporting post and the block having a bore for said plunger, and co-operating means associated with the block and the post for maintaining the plunger in and out of operative engagement with 20 the post.

14. The combination, with a reciprocable head and a tool, of a gag carried by the head and movable to connect the head and the tool on the power stroke of the head, and means other than the gag to disconnect the 25 tool from the head on the return stroke of the head.

15. The combination, with a reciprocable head and a tool, said head having an abutment adapted to engage the tool on the 30 power stroke of the head, of means other than the said abutment for automatically disconnecting the tool from the head on the return stroke of the head.

In testimony whereof, I hereunto affix my 35 signature in the presence of two witnesses.
